UNITED STATES PATENT OFFICE.

TRUE M. AVERY, OF GLENS FALLS, NEW YORK, ASSIGNOR TO UNION BAG & PAPER CORPORATION, OF NEW YORK, N. Y., A CORPORATION OF NEW YORK.

WEB CONTROLLER.

Application filed July 22, 1921. Serial No. 486,741.

To all whom it may concern:

Be it known that I, TRUE M. AVERY, a citizen of the United States, residing at Glens Falls, in the county of Warren and State of New York, have invented new and useful Improvements in Web Controllers, of which the following is a specification.

The present invention relates to improvements in web-controlling mechanism of the same general class as that shown and described in my prior Patent No. 1,256,286, granted February 12, 1918. The primary object of this invention is to provide an improved web-controlling mechanism whereby greater sensitiveness of control and, in consequence, greater precision are attained in the maintenance of correct registration between a longitudinally-moving web and a device or mechanism which cooperates with or operates on the web at points or within areas which are spaced in predetermined relation longitudinally of the web.

The invention is adapted for use generally in all situations where it is desirable or necessary to maintain correct registration between a travelling web and a device or mechanism which operates thereon or cooperates therewith in the manner above stated. For example, it may be employed in or as a part of a paper bag making machine for the purpose of maintaining correct registration between the continuous travelling web of paper from which the bags are to be produced and which bears printed advertisements or other impressions which are to appear on the completed bags, and the slitting, cutting or other device or devices in the machine which perform certain operations on the web in predetermined relation with the longitudinally-spaced imprints thereon; it may be employed in or as a part of a machine for cutting wall paper borders, for the purpose of maintaining accurate registration between the travelling web of printed wall paper border and the border trimming cutters; or it may be used in the printing art to secure accurate registration between successive imprints where, as for instance, in color printing, the printed matter is produced by a plurality of successive impressions. Other uses for the invention will suggest themselves and these are contemplated and will be included within the scope of the claims.

In the accompanying drawings:

Figure 1 is a side elevation of a paper bag making machine equipped with a web controller constructed in accordance with the present invention;

Figure 2 represents, on an enlarged scale, a vertical section on the line 2—2 of Figure 1;

Figure 3 represents a section on the line 3—3 of Figure 2, looking in the direction of the arrows;

Figure 4 represents a section on the line 4—4 of Figure 2, looking downwardly;

Figure 4^a is a top plan view of a portion of the machine showing the breaker or web cut-off device and part of the driving connection between it and the detector of the web controller;

Figure 5 represents a section on the line 5—5 of Figure 2, looking downwardly;

Figure 6 is a detail view of the detector which forms part of the web controller;

Figure 7 is a detail view partly in section, of the web-controlled member of the detector;

Figure 8 is a detail view of one of the collector rings and its cooperative brush forming part of the electrical mechanism of the controller;

Figure 9 represents, on an enlarged scale, a longitudinal section through the detector;

Figure 10 represents a transverse section through the web-controlled member shown in Figure 7, the section being taken on the line 10—10 of Figure 9;

Figure 11 represents a section on the line 11—11 of Figure 9;

Figure 12 represents a longitudinal section through the electrical elements of the detector on a different plane from that shown in Figure 9;

Figure 13 is a detail perspective view of the regulating contact of the controller; and

Figure 14 is a diagrammatic view showing the preferred electrical connections of the controller.

Similar parts are designated by the same reference characters in the several views.

Web-controlling mechanism embodying the present invention is applicable generally to all situations where it is desirable or necessary to maintain correct registration between a travelling web of paper or other

material, and a device or mechanism which operates on or cooperates with the web in predetermined relation to the length of the web. The invention enables the travelling 5 to be so controlled, while it continues to travel, that great accuracy or precision may be secured in the registration of the web with the device or mechanism which is designed and intended to register with it. This 10 result is accomplished, according to the present invention, by a detector, one element of which operates in invariable timed relation with the device or mechanism which is designed or intended to register with the web, 15 and another element of which operates in accordance with the actual movements of the web, devices being provided as a part of the detector which respond immediately to any variation in the speed of the web which 20 would tend to destroy or impair registration. A compensating drive of novel and improved construction serves to advance the web and this compensating drive is controlled by the detector in such a way that 25 the speed of the travelling web is increased or decreased as conditions may require, in order to maintain correct registration between the travelling web and the device or mechanism which cooperates with it. The 30 detector and compensating drive are so constructed and related that they are very sensitive to variations in the relation between the travelling web and the device or mechanism which is designed to register with it 35 and they are capable of responding immediately to increase or decrease the speed of the web and to thus maintain registration within very close limits.

The invention in the present instance is 40 shown applied to a paper bag making machine for the purpose of maintaining correct registration between the continuous travelling web of paper and the slitters, breaker or other parts of the machine which are intended to and should register very closely 45 with the web at predetermined intervals in its length during its passage through the machine, such an application of the invention being typical of other uses to which 50 the invention may be applied.

In this instance, the machine comprises generally a main frame 1 containing side members to support the operating mechanisms of the machine, such as printing rolls 55 2 adapted to imprint advertisements or other printed matter at predetermined intervals in the length of the web or strip of paper which is usually in the form of a tube, a gum-applying mechanism 3 adapted to apply adhesive to the web, slitters 4 adapted to operate on the web at predetermined intervals in its length and in definite relation to the imprints on the web, to form tabs or flaps which serve to secure the bottoms of 60 the completed bags, a pair of draw rolls

5 which function to draw the web through the machine, pinch rolls 6 which are arranged to act on the web after it has passed the draw rolls, a breaker 6^a which operates about midway between the draw rolls and 70 pinch rolls to completely sever the strip or web into bag lengths at points in definite relation with the printed impressions, and folding and cooperative bag forming mechanism 7, the construction and operation of which is well understood in the art, and hence requires no detailed description. A rack 8 may be provided at one end of the machine to support a roll of paper 9 on an arbor or shaft 10, so that the paper in the 80 form of a continuous strip or web is fed into the receiving end of the machine at a rate determined by the speed of the draw rolls 5.

The draw rolls 5, a pair of which may be used, as is shown, are mounted on shafts 11 and 12, these shafts being connected by suitable gearing 13 to insure rotation of the two draw rolls at equal speed, the draw rolls gripping the web between them and thus insuring advance of the web at a speed which will be determined by the speed of the draw rolls. One of the draw roll shafts, the lower shaft 11 in the present instance, is connected to the main drive shaft 14, through the medium of a compensator which, according to the present invention, is capable of increasing or diminishing the speed of the draw rolls and, in consequence, the speed of the web, under control of the detector, to compensate immediately for any slight variations which may occur between the imprints on the web and the slitters 4, or any equivalent device to be registered with the web. In the present instance, the main shaft 14 is provided with a gear which meshes with and drives an intermediate gear 16. This gear 16 in turn drives the pinch rolls 6 through an intermediate gear 17, and any suitable gearing connecting the latter to one of the pinch roller shafts, and this intermediate gear 17 also drives a gear 18 which forms part of the compensating drive for the draw rolls. The gear 16 also drives the slitters 4, through the medium of the gears 19 and 20, and the breaker 6^a is driven from and at equal speed with the pinch rolls by suitable gears 6^b. By this arrangement, the slitters, breaker and the pinch rolls will be driven at a definite speed in relation to the speed of the main drive shaft 14, but the draw rolls 5 are driven through a compensator which enables the draw rolls to be driven at a variable speed. The compensator comprises preferably a differential transmission which is driven from the main shaft at a speed in definite relation to the speed of the main shaft, but which is capable of transmitting motion to the draw rolls at an increasing and decreasing ratio. As shown, 115 120 125 130

the differential transmission comprises a member 21 which is fitted loosely on the draw roll shaft 11 and has the gear 18 fixed to it. This member is also formed with an internal gear face 22 with which a suitable number of pinions 23 cooperate, two pinions being preferred and shown in the present instance. The shafts or studs 24 on which the pinions are journalled are fixed to a worm wheel 25, this worm wheel being journalled on the shaft 11 and itself journalled in a bearing 26 which forms part of a gear housing 27 which latter is bolted or otherwise fixed to the adjacent side member of the main frame. The pinions 23 cooperate at the inner sides of their shafts 24 with a spur gear 28 which is keyed or otherwise fixed to the draw roll shaft 11.

In the construction as thus far described, motion will be transmitted from the gear 18 through the member 21 to the pinions 23 and the pinions in turn will drive the draw roll shaft 11 through the spur gear 28. If the worm wheel 25 which supports the journals of the pinions 23 is held stationary, the ratio of speed transmission between the main shaft 14 and the draw rolls would be constant, whereas, if the worm wheel 25 were rotated in either direction about the shaft 11, while the drive is taking place through the differential, the ratio of transmission between the main drive shaft 14 and the draw rolls will be increased or decreased according to the direction in which the worm wheel is rotated. The present invention provides relatively simple and efficient means for rotating the worm wheel 25 to vary the ratio of speed transmission through the differential mechanism and to thus compensate for any influences tending to destroy or impair correct registration between the travelling web and the slitters, breaker or other mechanism of the machine which depends upon registration with the web for the proper performance of its function. This compensating means, as shown, comprises a worm 29 which is fixed on a shaft 30, the upper end of this shaft being suitably journalled in the upper end of a bracket, which latter may form part of the gear housing 27. The lower end of the shaft 30 has a worm wheel 31 fixed thereon, and this worm wheel meshes with a worm 32 fixed on a shaft 33. The shaft 33 may be conveniently journalled in a bracket 34 bolted or otherwise fixed to the main frame and this shaft is driven by a reversible motor 35, a reversible electric motor being preferably used. Obviously, when the electric motor is running in one direction, it will cause the worm wheel 25 to revolve in a corresponding direction which, for example, may increase the ratio of speed transmission through the differential mechanism and consequently speed up the draw rolls to accelerate the travel of the web through the machine, whereas, while the motor is revolving in a reverse direction, the worm wheel 25 will be revolved in a direction opposite to that above described and, in consequence, the ratio of speed transmission through the differential device will, for example, be reduced, in consequence of which the draw rolls will operate at a relatively lower speed and the movement of the web through the machine will be thus retarded.

The present invention provides a relatively simple and efficient device for detecting within very close limits any lack of registration that may develop between the travelling web and the slitters, breaker or any other mechanism of the machine which depends upon such registration for the proper performance of its function. Preferably and as shown in Figures 5 to 14 inclusive, this detector comprises a shaft 36 which is journalled in suitable bearings on the main frame and a roll 37 over which the travelling web passes and which runs idly on the shaft 36. The detector is preferably located between the paper roll 9 and the printing mechanism 2, or in other words, it is located at the web-receiving end of the machine, as is shown in Figure 1, a suitable idler roll 38 being interposed between the detector and the paper roll to secure the necessary lap of the web around the detector roll when such is necessary. The detector shaft carries a sleeve 39 which may be composed of metal and provided with a set screw 40 by which it may be fixed to the shaft and to maintain a definite relation to the shaft during its operation. One end of this sleeve is formed with a shoulder 41 on which is fitted a cylindrical ball race 42. A ball cage or spacing ring 43 encircles the ball race 42 and contains sets of balls 44 and the bearing thus formed supports a member of the detector which is driven by and in exact accordance with the speed of the travelling web. In the present instance, this member is in the form of a toothed ring or sprocket 45 which is mounted on the series of balls 44 which encircle the ball race 42, the ring being thus supported for rotation relatively to the ball race 42 with a minimum resistance, and a driving connection is established between this ring and the travelling web, preferably through the equidistantly-spaced circumferentially-extending teeth or projections 46 which register with and engage in a series of correspondingly spaced perforations extending longitudinally of the web. These perforations in the web may be previously formed or they may be formed in the web at any time prior to its passage over the detector roll.

The sleeve 39 also carries a set of insulating bushings 47, 48, 49 and 50. These

bushings may be advantageously made of a suitable hard wood and they are non-rotatably fixed to the sleeve 39 by a key 51. The adjacent faces of the bushings are 5 formed with complementary grooves or recesses extending circumferentially thereof and these grooves or recesses formed between the bushings 47 and 48 receive a pair of segmental contact members 52 and 53 10 which form a gap 54 between them for the operation of a controlling contact 55 which is carried by the ring or member 45. The grooves or recesses in the adjacent faces of the bushings 47 and 48 and which receive 15 the contact members 52 and 53 are preferably undercut as indicated at 56, and end-pieces 57 having lugs to fit into these undercuts are secured by the screws 58 or otherwise to the ends of the contact members 52 and 53, these end-pieces being thus 20 adapted to retain the contact members 52 and 53 within the groove between the bushings, but permitting relative circumferential movement between these members to adjust the gap 54 between them and within 25 which the contact 55 operates. The adjacent ends of the bushings 48 and 49 are similarly grooved or recessed to receive a continuous metal collector ring 59 and the 30 adjacent ends of the bushings 49 and 50 are also grooved or recessed to receive a second continuous metallic collector ring 60. Dowell pins 61 may be fitted between these 35 collector rings and the respective bushings to insure rotation of the rings with the bushings, and the bushings, collector rings and the contact members 52 and 53 are all clamped firmly together preferably by a collar 62 which is threaded on the end of 40 the sleeve 39 opposite to the shoulder 41 and which acts to clamp the elements mentioned between it and the shoulder 41. The ball race 42 is held in place between the bushing 47 and a flange 63, the latter being secured to the end of the sleeve 39 adjacent to the roll 37 and held in place by 45 screws 64 or by other suitable means. The contact 55 which occupies a position in the gap 54 between the contact members 52 and 53 is mounted preferably on a rocker 65, whereby the contact may oscillate to a suitable degree and this rocker is pivoted on a shaft 66 supported on an arm 67 which latter is fixed to the ring or sprocket 45. The contact and its rocker are preferably 50 retained normally in a medial position, a spring 68 being provided for this purpose in the present instance, the intermediate portion of the spring being coiled about a pin 69 fixed to the arm 67 while the two arms 70 and 71 of the spring straddle the rocker shaft 66 and bear on opposite sides of a pin 72 carried by the rocker. By this arrangement, the two arms of the spring 55 which have a tendency to approach one another will normally bear against the opposite sides of the rocker shaft 66 and will be thus positioned to hold the rocker in a medial position, although the rocker may yield against the action of one or the other of the spring arms when engagement occurs between the contact and one of the contact members 52 or 53. This mode of mounting the controlling contact 55 is generally preferred, as it not only avoids impact or shock when it engages one of the contact members, but this arrangement enables the contact to be completed and to thus set the compensating drive into operation to restore correct registration of the web in the machine, without obstructing or interfering with the relative rotation that occurs between the ring or sprocket 45 and the detector shaft and the degree of which will depend upon the amount of variance between the web and the device or devices within the machine which are to be maintained in registration therewith. 70 75 80 85 90 95 100 105 110 115 120 125 130

The detector shaft 36, together with the contact members 52 and 53 and the collector rings 59 and 60 are driven in definite and constant timed relation with the slitters 4 and the breaker 6^a or any other part of the machine which is to be maintained in registration with the web. Any suitable gearing may be employed for this purpose, the gearing shown in the present instance comprising a longitudinal shaft 73 connected by equal-size bevel gears 74 to the shaft of the breaker, this shaft in turn driving, through equal-size bevel gears 75, a cross shaft 175 and a train of spur gears 176 leading to a gear 177. This gear 177 in turn meshes with a gear or pinion 76 on the detector roll shaft 36. During the 105 operation of the machine, this driving connection between the slitters, the breaker or an equivalent device and the detector roll shaft transmits motion to the latter at an invariable ratio to cause one revolution of the detector roll each time a bag length is cut off from the web by the breaker, but it may be necessary or desirable, preparatory to the starting of the machine, to permit the detector shaft 36 to be set manually to bring it into properly timed relation to the slitters, breaker, or other mechanism to be registered with the web. For this purpose, it is preferable to fit the driving gear or pinion 76 loosely on the detector roll shaft 36 and to couple it to said shaft by an appropriate clutch. For instance, as shown, one face of the gear 76 may be formed with a conical clutch face 77 to receive a complementary clutch member 78, the latter being splined on the detector roll shaft, through the key 79, and provided conveniently with a hand-wheel 80 which enables the detector roll shaft to be rotated manually to set it while the clutch is dis-

engaged. The clutch members are locked in engagement, after the detector roll has been properly set, by a milled head or nut 81 which is threaded on the end of the detector roll shaft, as shown.

A pair of brushes 82 and 83 bears continuously on the collector rings 59 and 60 respectively, these brushes, as shown, being provided with brush holders 84 and 85 which are suitably mounted on a stud or shaft 86 fixed to a part of the frame of the machine. The contact members 52 and 53 are connected respectively to the collector rings 59 and 60. Preferably and as shown in Figures 11 and 12, a pair of conducting pins 87 and 88 are fitted in a bore 89 formed in the bushing 48, and a compression spring 90 acts between these pins to force and hold them in contact with one of the contact members, the contact member 52 in the present instance. A similar conducting pin 91 is fitted in a bore 92 in the bushing 48 and bears against the other contact member 53 and this bore contains a compressed spring 93 which acts on a second conducting pin 94, the latter extending through an insulating bushing 95 in the collector ring 59 and making contact with the collector ring 60.

Suitable electrical connections are provided whereby the compensating motor 35 will be driven in a forward or reverse direction by the engagement of the controlling contact 55 with one or the other of the contact members 52 or 53. Preferably, a local battery circuit is provided for the controlling contacts of the detector, such a circuit being shown in Figure 14, wherein B represents a battery of suitable voltage, S represents a switch which may be provided to open the detector circuit when the machine is not in use, or when the machine is operated under conditions which do not require the use of the detector, as, for example, when plain paper is being run through the machine. The controlling contact 55 carried by the toothed ring or sprocket 45 may, as shown, be grounded on the machine and accordingly one terminal of the local battery circuit will be grounded on the machine. Preferably, the terminal of the local circuit which is to be grounded is connected to a contact 95 which is insulated from the machine but is to be connected to ground on the machine by a contact blade 96 which may be carried on the starting or controlling shaft 97 through which the machine is started and stopped, so that the detector will be thrown in and out of operation automatically, coincident with the starting and stopping of the machine. A relay R is preferably provided by which the local circuit of the detector may control the line or power circuit for the compensating motor 35 and this relay is capable of so controlling the line or power circuit as to cause the compensating

motor to run in a forward or reverse direction, according to the correction for registration which is to be made under control of the detector. As shown, the relay comprises a pair of electro-magnets 98 and 99 and a pair of cooperating armatures 100 and 101, these armatures being carried by spring contact blades 102 and 103 which are fixed at one end to a support 104 and carry contact points 105 and 106 at their opposite or free ends, to cooperate with corresponding contact points on the terminals 107 and 108 for the motor control wires 109 and 110 respectively, the blades 102 and 103 being connected to the line wire 111 of the motor circuit through preferably a fuse-block 112 and conductors 113. The other line wire 114 for the motor circuit is connected to a third terminal on the motor 35, it being understood that the motor shown diagrammatically in the present instance is of the type which will run in one direction when current is supplied thereto through the line wire 114 and the wire 109 and it will run in a reverse direction when current is supplied to it through the line wire 114 and the wire 110. The battery B of the local circuit is connected through the conductor 115 to both of the electro-magnets 98 and 99 and one of these electro-magnets, as, for example, the electro-magnet 98, is connected by the conductor 116 to the brush 83 which engages the collector ring 60, while the other electro-magnet 99 is connected by the conductor 117 to the brush 82 which engages the collector ring 59.

The mode of operation of a bag making machine embodying a web controller as hereinbefore described, is briefly as follows: The strip of paper from the paper roll 9 is threaded through the different mechanisms of the machine, it passing over the detector roll, between the slitters, between the draw rolls and between the pinch rolls and thence through the mechanisms which fold, cut and complete the bags in a manner well understood in the art. Usually in operating upon the web with the slitters, breaker, pinch rolls and bag folding and completing mechanisms, the strip of paper is of continuous length and usually of tubular form and has been previously printed with advertisements or other printed matter which it is desired should appear in uniform positions on the completed bags, the imprints on the strip being spaced at predetermined intervals longitudinally of the strip, as an incident to the printing thereof. Obviously, the slitting, cutting-off, and other operations performed on the strip to form bags therefrom must be formed in fixed or definite relation to the printed impressions on the strip; that is to say, these operations must be performed in registration with the printed impressions on the strip, in order to insure uniformity in the location of the printed impressions.

on the finished bags. The strip or web is drawn continuously through the machine by the draw rolls 5 and during the advance of the strip or web, the slitters 4, breaker or cut-off 6^a, and pinch rolls 6 operate thereon. Experience has demonstrated that uniformity in the speed of the strip or web and the maintenance of registration between it and the mechanisms of the machine which should 5 register with the strip can not be secured by the mere drawing of the strip or web through the machine by draw rolls which operate at a constant speed or at a speed in fixed ratio to the speed of the mechanisms 10 which are required to register with the strip, owing to slippage between the smooth faces of the draw rolls and the strip. According to the present invention, however, the slitters 4, breaker 6^a and pinch rolls 6, when 15 such are used, are driven at a fixed speed ratio relatively to the speed of the main drive shaft 14, but the draw rolls 5 are driven through a differential mechanism which is capable of varying the ratio of 20 speed transmission, in conjunction with a motor which is capable of acting on the differential to increase or diminish the speed of the draw rolls. In the particular construction shown, it will be understood that 25 if the worm wheel 25 remains stationary, the pinions 23 of the differential gearing will transmit motion to the draw rolls at a fixed ratio, but if the motor 35 runs in one direction, the worm wheel 25 will be 30 revolved in a direction to alter the ratio of speed transmission and thus increase the speed of the draw rolls and if the motor runs in a reverse direction, the worm wheel 25 will be revolved in a direction to alter the 35 ratio of speed transmission in a manner to reduce the speed of the draw rolls. The draw rolls constantly grip the strip or web and any variances which occur in the speed of the draw rolls will produce a corresponding 40 variation in the speed of the web. Working in conjunction with the speed compensator just described is the detector over which the web passes. The shaft 36 of the detector is driven, through the gearing previously 45 described, at a fixed ratio or in definite timed relation to the slitters 4, breaker or cut-off 6^a and also the pinch rolls 6 when the latter are used, and hence the contact members 52 will be caused to revolve 50 in proper timed relation to the slitters and breaker. An edge of the strip or web, which is provided with regularly spaced perforations, overlaps the contact controlling ring or member 45 which is very freely rotatable relatively to the detector shaft, and in order to cause rotation of this ring in exact accordance with the actual speed of 55 the strip or web, this ring is provided with teeth or projections which engage in the perforations in the web. By this arrangement, it will be understood that the contact members 52 and 53 are revolving in definite timed relation to the slitters, while the contact controlling ring 45 is revolving in accordance with the actual speed of the web. 60 When the web is moving at a speed which will insure correct registration between the printed impressions thereon and the slitters, breaker or equivalent mechanism in the machine, the contact 55 on the ring 45 will occupy a medial position in the gap 54 between the contact members 52 and 53, the contact 55 being then out of engagement with both of these contact members, in consequence of which the local circuit supplied 65 with current from the battery B will be open. The compensating motor 35 will then be at rest, the worm wheel 25 will be motionless and the ratio of speed transmission between the main drive shaft 14 and the draw 70 rolls 5 will be constant. However, in the operation of machines of this class, the rate of movement of the strip or web varies, it accelerating and retarding, owing to variations in the grip of the draw rolls on the 75 web, and it is the purpose of the present invention to prevent such variation to an extent that would cause an appreciable variation 80 in the registration between the web and the slitters, breaker or other mechanism of the machine. This result is accomplished by the detector operating in conjunction with the compensating motor. Should the speed of the web drop slightly, the contact-carrying ring 45 which is driven by or in 85 exact accordance with the speed of the web, will lag slightly relatively to the detector shaft 36 and this will bring the contact 55 on this contact ring into engagement with the adjacent end of the contact member 53. The engagement of these contacts closes the 90 local circuit through the electro-magnet 98, in consequence of which such magnet is energized and the contact 105 engages the terminal 107 and thus completes the line circuit 95 from the conductor 111 through the motor, in a manner to drive the motor 35 in a forward direction, and this motor operating 100 through the worm gearing previously described causes the worm wheel 25 to revolve 105 in a direction to vary the ratio of speed transmission in a manner to increase the speed of the draw rolls 5. As a result, the speed of the web will be increased to bring 110 the printed impressions thereon into correct 115 registration with the slitters, breaker or equivalent mechanism. On the other hand, should the speed of the web increase, the ring 45 which is driven by or in exact 120 accordance with the speed of the web, will be 125 carried into an advanced position of rotation relatively to the detector shaft which, as previously explained, is driven in fixed 130 timed relation with the slitters, breaker or equivalent mechanism. This action will 135

carry the contact 55 forward into engagement with the contact member 52 which revolves in unison with the detector shaft. As a consequence, the local circuit will be closed 5 through the electro-magnet 99 and energizing of this magnet will close the motor line circuit through the contact 106, terminal 108 and conductor 109, thus causing the motor 35 to revolve in a reverse direction. The 10 motor operating through the worm gearing will then revolve the worm wheel 25 in a direction to alter the ratio of speed transmission in a manner to diminish the speed of the draw rolls 5, in consequence of which 15 the speed of the strip or web will be reduced. In each instance, the compensating action of the motor 35 continues until the controlling contact 55 has returned to its medial position, thus opening the local circuit and 20 interrupting the operation of the compensating motor. However, the detector is very sensitive to variations in the speed of the strip or web relatively to the mechanism to which the detector is timed and also the 25 compensating motor corresponds immediately to correct the speed of the web under control of the detector.

In operating the machine shown in the present instance for the purpose of slitting, 30 cutting off and forming paper bags from a strip or web of paper having imprints at intervals in its length, the strip or web is usually printed on a suitable printing machine and perforations along one edge there- 35 of for the engagement of the sprocket teeth of the controlling contact are preferably made coincident with the printing operation. The subsequent passage of this printed and perforated strip through the machine employing slitters, breakers or other devices 40 which should register their operations with the printed impressions on the strip will insure correct registration in this respect through the operation of the detector and 45 the cooperative compensating motor.

Web-controlling means embodying the present invention insures registration within very close limits between a travelling web and a device to operate therein at predetermined intervals. The detector provided is 50 very sensitive to any variation in speed between the travelling web and the speed of the device which operates thereon, and the reversible motor responds immediately, under the control of the detector, to correct 55 any speed variation that may occur. It is particularly advantageous to employ a reversible electric motor to effect compensating for any speed variation, not only because of the facility of installation of the 60 motor, but also because the motor may remain coupled to the variable speed transmission means and hence it will act without lost motion or delay upon the variable speed 65 transmission means to promptly compensate

for any speed variation that may occur, thus reducing the variation in registration to the minimum.

The application of a reversible electric motor to the variable speed driving mechanism is substantially aided, and the compensating effect secured is materially improved by providing a system of worm gearing between the shaft of the motor and the element of the driving mechanism which 70 functions to vary the ratio of speed transmission therethrough, this being particularly so where, as in the instance herein shown and described, such element of the driving mechanism must sustain reaction from the driving force transmitted through the mechanism. By employing a system of worm gearing between such element of the driving mechanism and the motor, not only is the 75 desired speed reduction obtained between these parts with a relatively small number of gears, but the worms are capable of sustaining the forces exerted upon them by their respective worm wheels, arising from the reaction referred to, and hence the compensating motor, when de-energized, will 80 not be revolved under the influence of such reaction.

Obviously, the invention is capable of use 85 in many instances where it is desirable or necessary to control the speed of a strip or web substantially as described. For example where printed matter is applied to a strip or web by successive impressions as, for example, is done in color printing, the web controller can be used to maintain correct registration between the successive impressions. In such case, the detector shaft would be 90 driven in timed relation to the printing mechanism and the controlling contact 100 would be driven by or in accordance with the actual speed of the web. Similarly, in machines for trimming wall paper borders, the web controller may be used advantageously to maintain correct registration 105 between the printed border on the paper and the correspondingly shaped trimming cutters, in which case, the detector would be driven in timed relation to the trimming 110 cutters and the controlling contact would 115 be driven by or in accordance with the actual speed of the web.

I claim as my invention:—

1. A web controller comprising, in combination with web-advancing means, and a device operative on the web at predetermined intervals longitudinally thereof, a detector operative in response to variations in the speed of the web relatively to the speed of operation of said device, and means including a motor operative in forward or reverse direction under control of the detector for increasing or decreasing the speed of the web 120 relatively to the speed of operation of said device.

2. A web-controller comprising, in combination, with web-advancing means, and a device operative on the web at intervals in its length during its advance, a detector responsive to variations in the speed of the web in relation to the speed of operation of said device, variable speed driving means for the web-advancing means, and a reversible motor controlled by the detector and operative 10 on the variable speed driving means to compensate for variations in the speed of the web relatively to the speed of operation of said device.

3. A web-controller comprising, in combination, with web-advancing means, and a device to operate at intervals on the web during its travel, a detector responsive to variations in the speed of the web relatively to the speed of operation of said device, variable 15 speed driving means for the web-advancing means, and a reversible motor controlled by the detector and operative in response to variations in speed of the web to alter the ratio of speed transmission through said 20 driving means to accelerate or retard the speed of the web relatively to the speed of operation of said device.

4. A web-controlling means, comprising, in combination, with web-advancing means, 30 and a device to operate at intervals on the web during its travel, a speed-variation detector embodying cooperative electrical contacts timed in part in accordance with the speed of operation of said device and in part in accordance with the actual speed of advance of the web, variable-speed driving means for the web-advancing means, and a reversible electrical motor controlled in its operation and direction of rotation by the contacts of the detector and operative on said variable-speed driving means to increase or decrease the speed of the web-advancing means to bring the speed of the web into conformity with the speed of operation of said device.

5. A web-controller comprising, in combination, with web-advancing means, and a device to operate at intervals on the web during its travel, a detector having cooperative electrical contacts controlled in part in accordance with the speed of operation of said device and in part by the speed of the web, a local circuit including a relay controlled by the contacts of the detector, and means including a reversible electric motor capable of varying the speed of the web-advancing means, the operation and direction of rotation of the motor being controlled by the relay.

6. In combination with a web-controller comprising means for advancing a web, and a device adapted to register with and operate on the web, a detector for determining variations in speed between the web and the speed of operation of said device com-

prising opposed contacts having means for driving them in timed relation with said device, a cooperative contact having means for driving it in accordance with the actual speed of advance of the web, and a clutch between said device and said opposed contacts for altering the relation between them. 70

7. A speed-variation detector for web-controllers comprising a support carrying a pair of opposed contacts, a controlling member adapted to be driven in accordance with the speed of the web, and a controlling contact carried by the controlling member and arranged to engage one or the other of said opposed contacts, the controlling contact being movable relatively to the controlling member under the influence of its engagement with one of said opposed contacts. 75

8. A speed-variation detector for web controllers comprising a pair of opposed contacts revoluble in unison, and a controlling member rotatable relatively to said opposed contacts and carrying a controlling contact operative between and arranged to be engaged by one or the other of the opposed contacts, said controlling contact being mounted to swing, relatively to the controlling member, under the influence of its engagement with one or the other of the 95 opposed contacts.

9. A speed-variation detector for web-controllers comprising a support carrying a pair of circumferentially-spaced contacts which are rotatable in unison, a controlling member rotatable with and also relatively to said support, a controlling contact carried by said member and movable relatively to it in a circumferential direction, 100 under the influence of the engagement with one or the other of said opposed contacts, and means for restoring said controlling contact to a medial position after its deflection by one of the opposed contacts. 105

10. A speed-variation detector for web-controllers comprising a rotatable support carrying a pair of opposed circumferentially-spaced abutments, a controlling member freely rotatable relatively to said support and carrying a controlling abutment which is located in the paths of said opposed abutments, one of said abutments being yieldable circumferentially under the influence of its engagement with another of said abutments in consequence of relative rotation between said member and support. 115

11. A speed-variation detector for web-controllers comprising a support adapted to be revolved in accordance with the speed of an element of a machine and carrying opposed circumferentially-spaced abutments, a controlling member adapted to be revolved in accordance with the speed of a web and carrying pivotally an abutment which is arranged to be swung circumferentially rela- 125 130

tively to its carrying member under the influence of its engagement with either of the opposed abutments, and means for yielding-
ly holding said swinging abutment in a me-
dial position.

12. A speed-variation detector for web-
controllers comprising a support having
means for revolving it in accordance with
the speed of operation of an element of a
10 web-handling machine and carrying a pair
of circumferentially-spaced electrical con-
tacts, a member freely rotatable relatively to
said support and having means for revolving
it in accordance with the speed of a web,
15 a controlling electrical contact carried by
said member and arranged to be engaged by
either of said opposed contacts, said con-
trolling contact being pivoted to swing rela-
tively to said member in the circumferential
20 space between the opposed contacts, and
means for holding the controlling contact in
a medial position when not engaged by one
of the opposed contacts.

13. A speed-variation detector for web-
25 controllers comprising a rotatable support,
a pair of opposed contacts spaced and ad-
justable relatively to one another in a direc-
tion circumferentially of the support, and a
controlling member freely rotatable relative-
30 ly to said support and carrying a control-
ling contact arranged to cooperate with one
or the other of said opposed contacts in con-
sequence of relative rotation between said
member and support.

35 14. A speed-variation detector of the char-
acter described comprising a rotatable sup-
port formed with a circumferential groove,
a pair of segmental contact members in said
groove forming a circumferential gap be-
40 tween them, and a member rotatable rela-
tively to said support and carrying a con-
tact which operates in said gap.

15. A speed-variation detector of the char-
acter described comprising a support em-
45 bodying relatively axially movable bushings,
a pair of segmental contacts clamped in
a fixed relation between said bushings, and a
controlling member freely rotatable relative-
ly to said support and carrying a contact
50 arranged to engage one or the other of said
opposed contacts.

16. A detector of the character described
comprising a plurality of bushings having

complemental grooves formed in their adja-
cent ends, a pair of collector-rings fitted re-
spectively in the grooves between certain of
said bushings, a pair of segmental contact
members fitted in the grooves between others
of said bushings, conducting members be-
tween the contact members and the respec-
tive collector rings, and means for compress-
ing the bushings axially to clamp the col-
lector rings and contact members in fixed rela-
tion therewith.

17. A detector of the character described
comprising a roller carrying a pair of cir-
cumferentially spaced abutments, a toothed
annular member carrying a controlling abut-
ment which projects inwardly toward the
center of said member and cooperates with
said opposed abutments, and an anti-friction
bearing supporting said member for rotation
freely relatively to said roller.

18. A speed compensator for web-control-
lers comprising, in combination, a variable
speed mechanism for driving web-advancing
rolls, and a reversible motor connected to
drive the speed controlling element of said
mechanism in one direction or the other to
increase or decrease the speed at which the
web-advancing rolls are driven.

19. A speed compensator of the character
described comprising a variable speed mech-
anism, a reversible electric motor, and gear-
ing connecting said motor to a speed vary-
ing element of said mechanism to drive the
same in one direction or the other to vary the
ratio of speed transmission through said
mechanism.

20. A speed compensator for web-control-
lers comprising, in combination, web-ad-
vancing rolls, a variable speed mechanism
for driving said rolls, a reversible electric
motor, and a system of worm gearing con-
necting said motor to a speed-varying ele-
ment of said mechanism to drive such ele-
ment in one direction or the other to increase
or decrease the speed of the web-advancing
rolls.

In testimony whereof I have hereunto
set my hand in presence of two subscribing
witnesses.

TRUE M. AVERY.
